UNITED STATES PATENT OFFICE.

WILLIAM E. WUELKER, OF LOS ANGELES, CALIFORNIA.

POLISHING BRUSH.

Application filed March 7, 1923. Serial No. 623,448.

To all whom it may concern:

Be it known that I, WILLIAM E. WUELKER, a citizen of the United States, residing at Los Angeles, in the county of Los Angeles and State of California, have invented a new and useful Polishing Brush, of which the following is a specification.

This invention relates to a polishing brush that may be used for polishing surfaces such as those presented, for example, by the body and chassis of an automobile. This brush is adapted to be operated in any suitable manner to effect the polishing of a surface, and it is especially well adapted to 10 be connected with the chuck of the cleaning apparatus disclosed in my copending application for patent filed March 7, 1923, Serial No. 623,449.

An object of this invention is to provide 20 a brush of this type constructed in a manner to insure against scratching the surface being polished.

Another object is to provide simple and reliable means for holding a fabric cap or 25 cover upon a metallic member of the brush, which metallic member gives proper contour to the brush end.

The accompanying drawings illustrate 30 the invention:

Figure 1 is a side elevation of a brush embodying the invention, a portion of the stem being broken away to contract the view.

Fig. 2 is a longitudinal mid section of 35 Figure 1.

Figs. 3 and 4 are transverse sections on the lines indicated by 3—3 and 4—4, respectively, Figure 2.

Fig. 5 is an enlarged sectional detail 40 showing the ends of the lacing member and the clip connecting the same.

Referring to the drawings, there is provided a stem 11 of suitable construction for insertion in a chuck of the character, for example, disclosed in the above identified copending application. Assembled on a portion 12 of the stem 11 of reduced diameter, is a plurality of disks numbered from 13 to 31, inclusive. A greater or less number of 45 disks may, of course, be assembled on the stem. Though these disks may all be of the same diameter, I prefer that they increase gradually in diameter from end to end of the brush so that the brush will be more or less tapered and pointed in form. If desired, the disks 13 to 31 may have their

edges beveled so as to still further carry out the idea of making the brush gradually tapered.

Each of the disks 13 to 31 is provided 60 with a hole 32 to accommodate the stem 11. The said stem is provided with a shoulder 33 against which seats a rigid disk or washer 34 of metal or other suitable material, said disk 34 having a hole 35 to accommodate the stem. The disk 31 abuts the disk 34. The stem 11 projects beyond the disk 13 and said projecting end is threaded, as indicated at 36, to receive a nut 37 and a round faced cup shaped hollow end member 70 38. After the disks 13 to 31 have been assembled on the stem, a washer 39 is placed on the stem against the disk 13 and the nut 37 is then tightened against the washer 39, thus compressing the disks 13 to 31 firmly 75 between the washers 34, 39.

The end member 38 is tapered on its periphery and rounded at its outer end and is of somewhat less diameter than the disk 13 and is provided with a threaded socket 40 80 into which the threaded portion 36 of the stem is screwed. The member 38 is formed of metal or other rigid material and a cap 41 of felt or other suitable fabric is placed over the member 38 so as to completely 85 cover the same, the edge of the cap 41 abutting the disk 13, and the material of the cap being sufficiently thick so that the outside diameter of the end adjacent the disk 13 is the same as the smaller diameter of said 90 disk in order that the periphery of the cap will be flush with the periphery of the disk 13.

Suitable means are provided for securing the cap 41 in place on the member 38, and these means may be constructed as follows:

The member 38 is provided with a series of perforations 42 in its periphery and the cap is provided with recesses 43 and with perforations 44 at the opposite ends of said 100 recesses, the perforations 44 registering with the perforations 42. Before the member 38 is screwed upon the stem 11, the cap 41 will be placed on said member 38 and a lacing or thong 45 of leather or other suitable material will be strung in and out through the perforations 42, 44 so that the lacing will be arranged somewhat as indicated in Figure 4, the external portions of the lacing lying in the recesses 43 thus preventing the lacing from rubbing against 105 and scratching the surface being polished.

The ends of the lacing are brought together and secured in any suitable manner. In the instance shown, the ends of the lacing are connected by a suitable metal clip 46 which 5 is crimped about the end portions of the lacing, as clearly shown in Figure 5.

In using the brush, it will preferably be rotated by suitable mechanism, such, for example, as that disclosed in the above mentioned copending application. Though this 10 brush may be used for other purposes, it is especially useful for polishing, and the material of which the discs 13 to 31 inclusive and the cap 41 is made, may be felt or any 15 other material suitable for polishing.

It will be clear from the foregoing that, when the discs 13 to 31 and cap 41 become worn from use, they may be very easily removed from the stem and new ones substituted. By the construction described, the 20 brush is tapered and more or less pointed so as to facilitate entering the end of the brush into corners and other places that are difficult of access.

25 I claim:

1. In a polishing brush, the combination of a stem having a shoulder, a washer on the stem seated against said shoulder, a nut threaded on the stem, fabric disks between

the washer and nut, a rounded end member 30 threaded on the stem and covering the nut, and a polishing cap covering the end member and secured thereto.

2. In a polishing brush, the combination of a stem, a rounded end member secured to 35 one end of the stem, a cap covering said end member, means securing the cap to the end member, and means on the stem flush with the periphery of the cap forming a polishing surface.

3. In a polishing brush, the combination of a stem, a hollow member having perforations and threaded on one end of the stem, a cap fitting over and entirely covering the 40 hollow member, and a lacing laced in and out through the perforations and through the cap and having its end portions connected together within the hollow member.

4. In a polishing brush, the combination of a stem having a shoulder, a nut threaded 45 on the stem, means between the shoulder and nut forming a polishing member, an end member covering the nut and secured to the stem, and a cap secured to the end member.

Signed at Los Angeles, Calif., this 23d day of February, 1923.

WILLIAM E. WUELKER.
